CONTROL DESK HAVING CHANNEL-SHAPED FRAME MEMBERS

Conrad B. Myhre, Wilkinsburg, and Zwingle J. Dragar, Pittsburgh, Pa., assignors to Westinghouse Electric Corporation, East Pittsburgh, Pa., a corporation of Pennsylvania

Application October 25, 1944, Serial No. 560,334

4 Claims. (Cl. 312—141)

1

Our invention relates, generally, to switchboards and, more particularly, to switchboards of the control desk or benchboard type.

An object of our invention, generally stated, is to provide a control desk which shall be simple and efficient in operation and which may be economically manufactured and installed.

A more specific object of our invention is to simplify and improve the mechanical structure of a control desk.

Another object of our invention is to provide a control desk in which the frame is integral with the panels and wiring troughs.

Other objects of our invention will be explained fully hereinafter or will be apparent to those skilled in the art.

In accordance with one embodiment of our invention, channel-shaped members which constitute the frame and part of the panels of a control desk are utilized as wiring troughs, thereby eliminating the side sheets, additional cross members and uprights used in previous designs.

For a fuller understanding of the nature and objects of our invention, reference may be had to the following detailed description, taken in conjunction with the accompanying drawings, in which:

Figure 1 is a view, in transverse section, of a control desk comprising several sections and embodying our invention;

Fig. 2 is a view, in front elevation, of the center and adjacent sections of the desk shown in Fig. 1, portions of the adjacent sections being broken away;

Fig. 3 is a view, in plan, of one section and part of an adjacent section of the desk, portions of the cover members being broken away to show the manner of tying the desk sections together;

Fig. 4 is an enlarged view, in section, taken along the line IV—IV of Fig. 1;

Fig. 5 is an enlarged view, in section, taken along the line V—V of Fig. 1, and

Fig. 6 is an enlarged view, in perspective, of a portion of the desk structure.

Referring now to the drawings, and particularly to Figs. 1 and 2, the control desk shown therein includes a center section 10 with similar sections 11 and 12 joined onto opposite ends of the center section. It will be understood that as many sections as desired may be joined together when a desk is installed.

Each section comprises three basic parts, namely, a vertical portion 13, a sloping portion 14 and an apron portion 15. The vertical portion 13 comprises two spaced upright channel

2

members 16 and 17, which may be tied together at the top by angle members 18 and 19 and at the bottom by an angle member 21.

The sloping portion 14 comprises two channel members 22 and 23. One end of the channel member 22 is adjustably secured to the upright channel member 16 by brackets 24 and 25. One end of the other channel member 23 may be secured to the upright channel member 17 in a similar manner.

The apron portion 15 comprises a panel 26 having inturned edges 27 which form channel portions at the sides of the panel. The inturned edges 27 are adjustably secured to the other ends of the sloping channels 22 and 23 by brackets 28 and 29.

When assembling control desks of previous designs it has always been difficult to obtain good alignment between adjacent sections or units 20 of a complete desk. This has been due to manufacturing errors in the welded structural frame assembly, welded-on brackets, formed panels etc. In the present design this difficulty is precluded by bolting the three basic parts of each 25 section together by bolts which are inserted in slotted openings which afford the necessary range of adjustment to permit proper alignment of the various parts of the desk.

Thus, as shown, the bracket members 24, 25, 30 28 and 29 are provided with slotted openings 31. Similar openings may be provided in the channel members for the bolts which secure the members together, thereby permitting adjustment in either a vertical or a horizontal direction. The 35 bolting together of the basic parts of the desk provides ample rigidity and strength in all directions.

In this manner a control desk of sufficient strength and rigidity is provided without requiring the side sheets previously utilized in desks 40 of a similar type. The present structure also eliminates additional cross members and vertical uprights utilized in previous structures. Therefore, the present structure effects a saving 45 of approximately 30 per cent in steel, as compared with the material required for desks previously constructed.

In order to simplify the present structure still further, the channel members 16, 17, 22 and 23 50 and the channel portions formed by the inturned edges 27 of the panel 26 are provided with detachable cover plates, thereby providing wiring troughs within the channel members. Thus, relatively wide, flat cover plates 32 are provided for 55 portions of the upright channel members 16 and

17 and the sloping channel members 22 and 23. These cover plates may be detachably supported by U-shaped brackets 33.

As shown, angle-shaped cover plates 34 may also be provided for the channel members 16 and 17. These may be supported by angle-shaped brackets 35. Similar angle-shaped cover plates 36 may also be provided for the channel members 22 and 23. These cover plates may be supported by U-shaped brackets 37, as shown most clearly in Fig. 4.

As shown in Figs. 1 and 5, relatively narrow cover plates 38 may be provided for the channels formed by the inturned edges 27 of the apron panel 26. These cover plates may be supported by U-shaped brackets 39. In this manner the wires required for making the connections to the apparatus, usually mounted on a control desk of the present type, may be installed in the wiring troughs which are integral with the frame and panel members, thereby making it unnecessary to provide additional wiring troughs and gutters for the wires.

As shown in Fig. 1, terminal blocks 41 may be mounted at the front and the rear of the control desk when a pit is available underneath the control desk. Thus, the wires which are brought into the desk from other points may be connected to these terminal blocks. Similar terminal blocks may be provided at the ends of each section of the desk for cross panel wiring between sections, thereby eliminating wiring troughs between the different sections.

In accordance with the usual practice, a top cover member 42 is mounted on the upper ends of the upright channels 16 and 17. The cover 42 may be supported by the angle members 18 and 19 and a cross member 43, which rests on the angle members 18 and 19.

A removable panel 44 may be mounted at the rear of the upright panels 16 and 17 in the usual manner. An instrument panel 45 may be supported by brackets 46 secured to the upright channels 16 and 17.

As shown, a sloping panel 47 may be mounted on the sloping channel members 22 and 23. Angle members 48 may be provided at the ends of the panel 47 for additional support.

Removable braces 49 may be provided at the bottom of the desk to tie the apron part to the upright part during shipment. These braces are removed when the desk is installed in service.

As shown in Figs. 3 and 6, the sections of a multi-unit desk may be tied together by bolts 51. These bolts may be inserted through holes 52, see Fig. 1, provided through the U-shaped brackets which support the cover plates for the wiring troughs. In this manner, as many sections as required may be tied together when the desk is installed, and additional sections may be added at a later date, if desired.

From the foregoing description it is apparent that we have provided a control desk which effects a considerable saving in the amount of material required to construct the desk. Furthermore, the simplicity of construction and minimum number of parts reduce the manufacturing and assembly time, thereby still further reducing the overall cost of the desk.

The installation of the desk is simplified since the different sections may be readily bolted together and aligned in the manner hereinbefore described. The present structure has an additional feature of flexibility in that desks of the high or low type utilize the same parts through-

out, except for the upright members at the rear of the desk, the length of which may be readily increased, if desired.

Since numerous changes may be made in the above-described construction, and different embodiments of the invention may be made without departing from the spirit and scope thereof, it is intended that all matter contained in the foregoing description or shown in the accompanying drawing shall be interpreted as illustrative and not in a limiting sense.

We claim as our invention:

1. A control desk comprising, a pair of spaced upright channel members, horizontally disposed members for tying the upright members together, side channel members each having one end secured to one of the upright members, a panel member having inturned edges forming therewith integral channel portions secured to the other ends of the side channel members, detachable cover plates for said channel members and the channel portions of said panel member, and brackets for supporting said cover plates substantially flush with the edges of the channels, thereby providing wiring troughs within said members.

2. A control desk section comprising, a pair of spaced upright channel members, horizontally disposed members for tying the upright members together, side channel members each having one end adjustably secured to one of the upright members, slotted brackets for adjustably securing said members together, a panel member having inturned edges forming therewith integral channel portions adjustably secured to the other ends of the side channel members, detachable cover plates for said channel members to provide wiring troughs within said members, and brackets for supporting said cover plates substantially in alignment with the edges of the channels, certain of said brackets having openings therein for utilization in attaching said desk section to an adjacent desk section.

3. A control desk section comprising, a pair of spaced upright channel members, horizontally disposed members for tying the upright members together, a pair of side channel members, bracket means for adjustably attaching one end of each side channel member to one of the upright members, a panel member having channel-shaped portions integrally formed at its edges, bracket means for adjustably attaching the edges of the panel member to the other ends of the side channel members, detachable cover plates for said channel members to provide wiring troughs within said members, and brackets for supporting said cover plates substantially in alignment with the edges of the channels, certain of said brackets having openings therein for utilization in attaching said desk section to an adjacent desk section.

4. A control desk comprising, a pair of spaced upright channel members, horizontally disposed members for tying the upright members together, a pair of side channel members, means for adjustably attaching one end of each side channel member to one of the upright members, a panel member having channel-shaped portions integrally formed at its edges, means for adjustably attaching the edges of the panel member to the other ends of the side channel members, detachable cover plates for said channel members and the channel portions of the panel member, and brackets for supporting said cover plates substantially flush with the edges of the channels,

thereby providing wiring troughs integral with
said members.
